RELAY

Edgar D. Lilja, Rockford, Ill., assignor to Barber-Colman Company, Rockford, Ill., a corporation of Illinois

Application August 3, 1940, Serial No. 350,397

10 Claims. (Cl. 200—93)

The invention relates to relays and particularly to polarized relays.

The primary object of the invention is to provide a relay having extreme sensitivity.

The important increase in sensitivity which I attain is believed to be in large measure attributable to the utilization of a fundamentally new combination of operating principles for relays as a class, as will hereinafter more fully appear.

Another object of the invention is to provide a polarized relay characterized not only by its high sensitivity, but also by its ruggedness and simplicity of construction which achieve long life, effectualness of operation and low cost.

The invention also resides in certain novel combinations and arrangements of the relay parts by virtue of which adverse effects of mounting vibration and power frequency response are minimized.

Further objects and advantages of the invention will become apparent as the following description proceeds, taken in connection with the accompanying drawings in which:

Figure 1 is a general perspective view of a relay embodying the invention.

Fig. 2 is a longitudinal sectional view taken substantially along the line 2—2 in Fig. 1, and being in effect a stop-motion view since it indicates the flux distribution which is effective to shift the armature from the position shown over to the left hand position indicated in Fig. 3.

Fig. 3 is a longitudinal sectional view similar to Fig. 2 but showing the relay armature as having completed its shift to the left.

Fig. 4 is a longitudinal sectional view similar to Fig. 3 but indicating the current and flux paths during a current cycle alternate to that indicated in Fig. 3.

Fig. 5 is a longitudinal sectional view similar to Fig. 3 but showing the relay armature in its right hand position.

Fig. 6 is a transverse sectional view taken substantially along the line 6—6 in Fig. 2.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In the instant exemplification the invention 55

has been shown as embodied in an alternating current polarized relay. This relay comprises a pair of stationary contact points 10 and 11 on the ends of respective ones of a pair of adjusting screws 12, 13 threaded in supports 14 which may be mounted on a panel or other suitable base (not shown). Between these stationary contact points 10, 11 is a double contact 15 fixed on a resilient spring tongue or finger 16, anchored 10 in cantilever fashion at its upper end on a U-shaped metal bracket 17 and flexible to right or left to close the movable contact 15 against one or the other of the stationary contacts 10, 11 and thereby close corresponding controlled 15 circuits (not shown). Of course, when the movable contact 15 is in its central or mid-position it is out of engagement with both of the stationary contacts 10, 11 and both of the alternatively closable controlled circuits are open.

20 Adjustment of the bracket 17 may be made to vary the initial position of the tongue 16 and its contact 15. For this purpose the bracket is pivoted on a pin 17^a fixed to a suitable base and the bracket is urged into frictional engagement with the face of the base or panel by a compression spring 17^b encircling the pin 17^a and interposed between the inner arm of the bracket and a collar 17^c on the pin. To adjust the angular position of the bracket 17 about the pin 17^a, a screw 17^d is threaded in or out, this pin being arranged 30 to bear against a fixed abutment 17^e. A tension spring 17^f, anchored to the inner bracket arm and to the base, yieldably holds the nose 35 of the screw 17^d against the abutments 17^e.

The actuating mechanism for the relay comprises a horizontal plunger or armature 18 of iron or other magnetizable material. This plunger is fixed by screws 18^a at its opposite ends 40 to stiffener extensions 18^b on the lower extremities of depending spring fingers 19, which are anchored at their upper ends to the arms of a bracket 20 also fixed on the base (not shown). These fingers 19 are in turn connected through 45 contractile springs 21 with the central contact's finger 16. Accordingly, when the plunger 18 is shifted endwise to the left (position shown in Fig. 3) the central finger 16 is flexed to close the contact 15 against the stationary contact point 10. Similarly, when the plunger 18 is shifted axially to the right (the position shown 50 in Fig. 5) the central finger 16 is pulled over to close the contact point 15 against the contact 11; and when the plunger 18 rests in its centered or mid-position, the movable contact 15

is similarly centered out of engagement with the stationary side contacts 10, 11.

The electromagnetic actuating system for shifting the plunger 18 is next described below. Before proceeding to that it should be noted, however, that the utilization of the contractile springs 21 to interconnect the actuating plunger 18 and the movable contact finger 16 is especially advantageous. The interposition of these springs 21 in the system of moving parts substantially prevents the transmission of vibratory forces from the plunger 18 to the contact finger 16 or, in other words, minimizes any chattering of the contact points which might otherwise be caused by the power frequency response of the plunger. This spring arrangement also minimizes the effect of any vibration of the supporting base from which the fingers 10 are hung and which would otherwise tend to shake the center finger 16 with resultant chattering of the contact points. Further damping out of undesirable plunger vibration is also afforded by a brake comprising a resilient wire 29 (Figs. 1 and 2) fixed to one of the spring extensions 19^a and arranged to ride frictionally over a pin 30 as the plunger 18 moves back and forth. Endwise movement of the plunger is limited by stops at each end, one of which is shown in Fig. 1 as a bracket 31 presenting a felt button 31^a to the adjacent portion of the spring extension 19^a to limit the latter's outward swing.

In the exemplary electromagnetic system shown (see Fig. 2) the plunger 18, which constitutes the movable armature of the system, projects axially through a casing or stator structure, designated generally as 22, and comprising a cylindrical sleeve 23. This casing also includes end walls 24, rigid with the sleeve 23, and centrally apertured as at 25 for free passage of the ends of the plunger 18, with a fairly large air gap between the adjacent plunger and casing parts as shown. For example, if the casing 22 has an outside diameter of 1 $\frac{1}{4}$ inches, the plunger diameter may be 0.265 inch and the holes 25 may be of a diameter to give an air gap from their edges to the main body of the plunger of 0.036 inch. In such case the overall length of the casing may be 2 $\frac{1}{2}$ inches, the main or unreduced portion of the plunger 2 $\frac{1}{2}$ inches long, the end members 24 may be $\frac{1}{8}$ inch thick and the sleeve 23 may be $\frac{1}{16}$ inch thick. Additionally, a center partition 26 is provided in the sleeve 23, being rigid with the latter and centrally apertured as indicated at 27 for free passage of the plunger. The entire casing 22 is made of iron or other ferromagnetic material and serves, in conjunction with the plunger 18, to form various flux paths as hereinafter more particularly described. The casing 22 is, like the contact structure, supported on a suitable base (not shown) and particularly to be noted is the fact that none of its parts touch or rub against the plunger 18 so that there is no friction to impede or interfere with the latter's free movement except the adjustable amount provided by the brake 29, 30 for damping purposes. This is, of course, important in a sensitive device such as the one herein disclosed.

Within the casing 22, and encircling the plunger 18, are two polarizing windings PW₁ and PW₂, and two control windings CW₁ and CW₂, arranged in pairs so that the polarizing winding PW₁ and the control winding CW₁ encircle one end portion or substantially half of the plunger 18 and the other two windings PW₂ and CW₂ encircle the other half. For this purpose the

75 pairs of windings are wound on insulating spools 28, snugly fitted in the sleeve 23. Note that the center partition 26 is made up of two abutting apertured ferrous disks seated in annular recesses in the opposed ends of these spools, the thickness of each disk being substantially that for one of the end members 24, although the central apertures are slightly larger than those in the end members. The polarizing windings PW₁, PW₂ are continuously excited from a suitable source of alternating current, the instantaneous direction of current flow for one half cycle being indicated by the dotted arrow line I_p in Figs. 2 and 3. It may be noted, incidentally, at this point that the direction of current flow in the alternate half cycles is indicated by the dotted arrow line I_p in Fig. 4. The control windings CW₁ and CW₂ are, on the other hand, excited with an alternating current having a controlled and variable phase relation with respect to the current in the polarizing windings, and in the exemplary construction the connections of the control windings are such that the directions of current flow in the two are opposed with respect to each other, as indicated by the arrow line I_c in Fig. 2. As a generalization it may be noted that for one phase relation between I_p and I_c the magnetomotive forces set up by the windings PW₁ and CW₁ aid each other while those of the other pair of windings, namely PW₂ and CW₂, buck or oppose each other, so that the plunger 18 moves to the left (to the position shown in Fig. 3) that is, toward the aiding coils. Similarly, for another or opposite phase relation of the currents I_p and I_c the magnetomotive force of the windings PW₂, CW₂ aid each other while those set up by the windings PW₁ and CW₁ oppose, and the plunger 18 moves in the opposite direction, that is, to the right (to the position shown in Fig. 5). It will readily be understood by those skilled in the art that the same general effect noted can be obtained by using oppositely wound (with respect to each other) polarizing windings and like wound control windings rather than like wound polarizing windings and oppositely wound control windings as shown. The details of the fluxes set up by the windings shown and their action on the plunger, under different current phase conditions, will appear more fully below.

The significance of the structural arrangement set out above will become apparent on connection with an analysis of the relay's operation, for, unexpectedly enough, it will be found that the relay involves quite a fundamentally new combination of operating principles, insofar as relays are concerned. In general, it should be borne in mind that similar relays have heretofore commonly operated as a result of what may be termed "solenoid action." The relay herein shown utilizes not only such a solenoid action, but also supplements it with what may be termed a "motor action." It is the utilization of this latter departure from prior practice which apparently accounts in large measure for my relay's unusual sensitivity.

By "solenoid action" I have reference to the tendency of a movable magnetizable element, threaded by flux, to move into a position in the flux or magnetic field in which the reluctance of the path for the flux is a minimum. For example, in the structure shown (see Fig. 2) the plunger 18 tends to move endwise in one direction or the other (the direction in any particular case being dependent upon the preponderance of the flux threading one end or the other of the

plunger) to a position in which the gap is minimized between the plunger and the one of the casing end walls 24 at which the flux is a maximum. Thus, if there is more flux between the left end wall and the plunger than between the right end wall of the casing and the plunger, the plunger will tend to move to the left so as to minimize the length of the air gap between this left end wall and the plunger, such motion being due to the so-called "solenoid action." A similar action, in the opposite direction, takes place when the greater amount of flux threads the right hand end of the plunger. It should be observed, incidentally, that it is only the amount, and not the polarity, of the net flux which is important. Thus, when using an alternating current to set up the flux, the polarity of the flux will reverse for each half cycle of the current. Two such opposite directions of current flow are indicated respectively in Figs. 3 and 4. In both cases, however, the preponderance of flux at the left end of the plunger tends to move the latter to the left, even though the directions of the flux are, in the two instances shown, opposite to each other.

As to "motor action," I have reference to the well known phenomenon commonly referred to as defined by Ampere's law, namely that when a current carrying conductor lies at right angles to the lines of force in a magnetic field a force is set up tending to displace the conductor in the field.

In the present instance the plunger 18 is, in a general sense, utilized both as a movable magnetic member in a solenoid action system and as a movable conductor in a motor action system, the effects of the two actions on the plunger being made cumulative.

Turning now to the application of these factors in the particular structure shown, it will be observed, upon reference to Fig. 2, that the current I_p of the polarizing windings PW₁ and PW₂ sets up a flux f_p flowing through a long orbital path including the full length of the plunger or armature 18. The control windings CW₁, CW₂, on the other hand, set up fluxes f_{c1} and f_{c2} , respectively, in the two shorter orbital paths indicated, which extend through respective halves of the plunger 18 and have in common only the intermediate portion or center partition 26 of the stator. In the left hand portion of the magnetic structure the fluxes f_p and f_{c1} aid each other to produce a net flux f_{n1} threading the gap between the end of the plunger 18 and the left end wall 24 of the casing. The fluxes f_p and f_{c2} buck each other, however, so that a smaller net flux f_{n2} links the plunger 18 and the right hand end wall of the casing. The relative magnitudes of the fluxes are indicated roughly by the corresponding lengths of the arrows. Under the circumstances noted, the solenoid action of the preponderating net flux f_{n1} tends to cause the plunger 18 to shift to the left to the position shown in Fig. 3.

The solenoid action described just above is, however, augmented by an important motor action which the fluxes noted also set up. In this connection it should be observed particularly that the plunger 18 is traversed from end to end by flux which has a minimum value, even in its right hand portion, of f_{n2} . When a piece of magnetizable material, such as the plunger 18, is traversed by flux, the individual atoms in the material are realigned by the impressed field or flux in such a way that the combined effect of their electron spins may be represented by a current sheath

banding the part. This sheath current for the plunger 18 is indicated by the arrows I_s in Fig. 6. At the mid-portion of the plunger 18, however, a net flux f_{n3} , equal to the sum of f_{c1} and f_{c2} , threading between the plunger 18 and the partition 26, cuts across the path of this sheath current. Accordingly, a motor action is set up between the sheath current and the crossing flux f_{n3} , which also tends to shift the plunger 18 to the left. The polarizing windings PW₁, PW₂ determine the polarity of the sheath current, and the polarity impressed on the control windings, relative to that of the polarizing windings, determines the polarity relationship between the sheath current and the net flux f_{n3} entering the mid-portion of the plunger, which relation in turn determines the direction of the force on the plunger resulting from the motor action. With the flux and sheath current polarity relation indicated in Figs. 3 and 6 the motor action would be to the left (as determined by the so-called "left-hand rule") or, in other words, in a direction to augment the solenoid effect.

Substantially the same type of operation takes place when the phase of the control current in the windings CW₁, CW₂ is altered so as to shift the plunger 18 to the right and close the movable contact 15 against the stationary contact 11. In such case the flux f_{c2} , set up by the control winding CW₂, aids the polarizing winding flux f_p , while the flux f_{c1} , set up by the other control winding CW₁, opposes the flux f_p of the polarizing windings. Accordingly, the net flux f_{n2} exceeds the net flux f_{n1} so that the resulting solenoid action on the plunger tends to move it to the right, to the position of Fig. 5. Furthermore, the polarity relation is reversed between the net flux f_{n3} at the mid-portion of the plunger and the sheath current, so that the effect of the motor action is also reversed and tends to shift the plunger to the right.

To restore the plunger 18 to its neutral or mid-position the voltage applied to the control windings CW₁, CW₂ may be reduced to zero, whereupon only the polarizing windings are effective, and since their effect is balanced there will be no force tending to move the plunger in either direction and it will return to its mid-position.

From the foregoing, it will be appreciated that a very simple relay structure has been provided. Despite this structural simplicity the very unusual operating characteristics of the relay afford a high degree of sensitivity, particularly adapting the relay for use in various types of control circuits where such sensitivity is often of paramount importance.

I claim as my invention:

1. A polarized relay comprising, in combination, two polarizing coils and two control coils arranged in axially aligned pairs with one control coil and one polarizing coil in each pair, the polarizing coils being arranged to produce magnetomotive forces of the same polarity with relation to respective ends thereof but the control coils being arranged to produce magnetomotive forces of opposite polarity with relation to their respective ends, an elongated armature core projecting axially through said pairs of coils, means supporting said armature for free endwise movement, switch means actuated in opposite senses by movement of the armature in respectively opposite directions, and means forming a low reluctance return path for flux set up in said armature core by said coils and extending from one end of said armature to the other end with a

by-pass extending from its mid-portion and between said pairs of coils to a point adjacent the mid-portion of said armature.

2. A polarized relay comprising, in combination, an elongated magnetizable armature, means supporting said armature for endwise movement, switch means actuated by movement of said armature, a stator of magnetizable material including three spaced members projecting in proximity respectively with the two end and mid-portions of the armature and having end portions remote from the armature all joined together to form three low reluctance flux paths linking said armature, one path extending lengthwise through the armature and including the stator members at its ends, the second extending through the portion of the armature between its mid-portion and one of said members at one end of the armature, and the third extending between the mid-portion of the armature and said member at the opposite end of said armature, means including a polarizing winding for inducing a flow of flux through said one path, and means including a pair of control windings for inducing a flow of flux through respective ones of said second and third paths.

3. A polarized relay comprising, in combination, an elongated magnetizable armature, means supporting said armature for endwise movement, switch means actuated by movement of said armature, a stator of magnetizable material including three spaced members projecting in proximity respectively with the two end and mid-portions of the armature and having end portions remote from the armature all joined together to form three low reluctance flux paths linking said armature, one path extending lengthwise through the armature and including the stator members at its ends, the second extending through the portion of the armature between its mid-portion and one of said members at one end of the armature, and the third extending between the mid-portion of the armature and said member at the opposite end of said armature, means including a polarizing winding for inducing a flow of flux through said one path, and means including at least one control winding for inducing a flow of flux through one of said second and third paths.

4. In a relay, the combination of a switch, an elongated movable actuating plunger of magnetizable material for said switch, a stator of magnetizable material adjacent said plunger, means for setting up a magnetic field linking said plunger and stator to draw the plunger toward the stator by solenoid action, said field traversing the plunger endwise, and means for setting up a magnetic field cutting substantially at right angles across the sheath current banding said plunger substantially adjacent the mid-portion of the latter by reason of the flux traversing it endwise and with a polarity relative to that of the sheath current such as to produce a motor action tending to augment said solenoid action in moving the plunger.

5. A polarized relay comprising, in combination, a movably mounted armature of magnetizable material, a magnetizable stator having portions in proximity to two spaced points on the armature and joined by a portion remote from the armature, said stator also including an intermediate portion extending from said remote portion into proximity with a point on the armature intermediate the first mentioned points, two polarizing windings arranged to produce fluxes

of like polarity traversing said armature between said two points in an orbital path including the armature and said first mentioned two portions of the stator and said remote portion of the latter, and two control windings arranged to produce fluxes of opposite polarity to each other traversing respective orbital paths having in common only said intermediate portion of the stator.

10 6. In a relay, the combination of a movably mounted armature of magnetizable material, a magnetizable stator having portions in proximity to two spaced points on the armature and joined by a portion remote from the armature, said stator also including a portion extending from said remote portion into proximity with a point on the armature intermediate the first mentioned two points, and exciting means for producing flux threading an orbital path extending through the armature between said two points and through the first mentioned portions of the stator adjacent said points and through said remote portion of the stator and for also producing a flux threading a second orbital path extending only through that portion of the armature lying between said intermediate point and one of said first mentioned points.

20 7. In a relay the combination of a movably mounted armature of magnetizable material, a magnetizable stator having portions in proximity to two spaced points on the armature and joined by a portion remote from the armature, said stator also including an intermediate portion extending from said remote portion into proximity with a point on the armature intermediate the first mentioned points, and exciting means for producing flux threading an orbital path extending through the armature between said first mentioned points and through the first mentioned portions of the stator adjacent said points and through said remote portion of the stator and for also setting up flux traversing the gap between said intermediate point on the armature and said intermediate portion of the stator to cut across

45 a sheath current banding the armature and set up by the first mentioned flux traversing it.

8. A polarized relay comprising, in combination, a tubular casing having end walls and a transverse central partition, all of magnetizable material, said end walls and partition having aligned central apertures therein, an armature core comprising a continuous length of magnetizable material, means supporting said armature in a position in which it extends 50 through said apertures and for free endwise movement, switch means actuated in opposite senses in response to movement of said armature in respectively opposite directions, two polarizing windings in respective halves of the casing defined by said partition and encircling said armature, and two control windings also disposed in respective halves of the casing defined by said partition and encircling said armature, said polarizing windings being arranged to produce 55 fluxes of like polarity traversing said core and said control windings being arranged to produce fluxes of opposite polarity to each other traversing the portions of said armature which they encircle.

70 9. In a relay, the combination of two resilient spring fingers each fixed at one end to depend from such fixed end in generally parallel spaced relation, an elongated magnetizable armature fixed between and carried by the lower end portions of said fingers, means including an elec-

tromagnetic actuator freely encircling said armature and out of contact with it for moving the same endwise, a laterally movable switch member disposed between said fingers, cooperating stationary switch members on each side of said movable switch member and alternatively engageable thereby, and contractile springs operatively connecting said movable switch member and the fingers on opposite sides thereof.

10. In a relay, the combination of two elongated members disposed in spaced generally vertical positions, said members being free for lateral swinging movement, an elongated magnetizable armature fixed between portions of said

members remote from their upper ends and carried thereby for endwise movement upon lateral swinging of said members, means including an electromagnetic actuator encircling said armature for moving the same endwise, a laterally movable switch member disposed between said vertical members, cooperating stationary switch members on each side of said movable switch member and alternatively engageable thereby, and contractile springs operatively connecting said movable switch member and the vertical members on opposite sides thereof.

EDGAR D. LILJA.
